UNITED STATES PATENT OFFICE.

FRANCIS MORTON CLARK, OF GARDEN CITY, NEW YORK.

MECHANICAL STOKER.

1,167,627.

Specification of Letters Patent. Patented Jan. 11, 1916.

Application filed April 14, 1914. Serial No. 831,783.

To all whom it may concern:

Be it known that I, FRANCIS MORTON CLARK, a citizen of the United States, and a resident of Garden City, in the county of 5 Nassau and State of New York, have invented a certain new and useful Improvement in Mechanical Stokers, of which the following is a full, clear, and exact description.

My invention is an improvement in mechanical stokers and its principal objects are the provision of a stoker of the chain grate type in which the grate bars may have a limited movement with relation to the conveyer chains (which latter may always be 15 maintained in taut condition) and the furnishing of novel and efficient means for moving the grate bars relatively to one another at certain points in their travel to aid in preventing the formation of clinker 20 or large masses of comparatively impervious coke and to break up such masses if already formed.

Further and more detailed objects and advantages of my invention will later appear 25 in the specification and be pointed out in the appended claim.

In the three sheets of drawings accompanying this application and forming a part hereof Figure 1 is a partial vertical section of a furnace, boiler, and a stoker embodying my invention, certain of the parts appearing in side elevation; Fig. 2 is a perspective view of an agitator bar employed to give the relative movement to the grate 35 bars, a portion of the retaining strut for said agitator bar being also shown; Fig. 3 is a side view of one form of grate bar section which may be employed in my invention; Fig. 4 is a side view of a series of 40 grate bar sections assembled to form a grate bar, the sections illustrated having different points of contact for the agitator bar from that shown in Fig. 3; Figs. 5 and 6 show still other modified forms of grate bar sections; Fig. 7 is a partial side view of one 45 of the idler shafts of the stoker showing the agitator bar in vertical section and means for preventing lateral displacement of the agitator bar; Fig. 8 is an end view on a 50 larger scale of a portion of the chain grate,

showing the position assumed by one of the modified forms of grate bar when in elevated position; and Fig. 9 is a perspective view of one of the conveyer chain links.

Referring to the drawings, 10 indicates a 55 boiler, 11 an ignition arch in cross section and 12 one of the side frames of a stoker.

For the purposes of describing my invention I have only indicated a portion of the grate in Fig. 1 and have omitted the details 60 of the actuating mechanism therefor, as these details form no part of the present invention and any well known type of actuating means may be employed. The grate is of the endless chain type, in which conveyer chains 13 are employed and the grate bars which are carried by these chains extend 65 transversely across the furnace. These grate bars may be a unit but I prefer to make them in sections joined end to end, as illustrated 70 in Fig. 4. In the preferred form shown in the drawings the chains 13 are formed of links 14 (see Fig. 9) which are provided on one side with a hook 15 and on the opposite side with an eye 16 by means of which they 75 are connected into an endless chain. Transversely of each link 14 there is provided a socket 17 having slightly flaring vertical walls, which socket is for the reception of the correspondingly tapering webs of the 80 grate bar sections, and holes 18 through the vertical walls of the sockets are provided for receiving attaching means to hold the grate bar sections in place.

Modified forms of grate bar sections are 85 shown in various figures of the drawings but all are attached to the chains in the same manner. A pair of vertically elongated openings 19, 20 are provided near each end of each section, the distance of the openings 90 19 from the end of the section being slightly less (to allow for irregularities in fitting) than half the distance between the openings 19 and 20 and the latter being equal to the distance between the holes 18 in the link 95 14. If the section is to be attached to an outside conveyer chain the section is placed so that the cotter pins 21 secure the section by passing through the openings 19 and 20 and the pair of holes 18. On the other hand 100

if the attachment is to be made to an intermediate chain, the respective sections only part way enter the sockets 17 and a single cotter pin passing through the openings 19 5 attaches the section.

As previously stated, the openings 19, 20 are elongated in a vertical direction, this being for the purpose of allowing the sections a limited vertical movement with respect to the chains, the movement being for 10 the purpose of preventing or breaking up clinker and masses of coke and thus affording thorough aeration of the fire. For the purpose of giving this vertical movement to 15 the grate bar sections I provide underneath each section one or more agitator bars 22, shown in position in Fig. 1 and in enlarged view in Fig. 2. These bars, which I show as made in inverted V-shape in cross section 20 for convenience in making by casting, are supported by the idler shafts 23 and are held in place against longitudinal displacement by a bolt 24 passing through the strut 25 which extends from one side of the frame 25 to the other. The bolt 24 is threaded as shown and a nut 26 engaging the front side of the strut 25 forms a means of adjusting the agitator bar in a lengthwise direction. The lower surface of the agitator bars is 30 provided with inclined portions 27 adjacent the points of support on the shafts 23 so that by tightening the nuts 26 and drawing the agitator bars toward the front of the furnace the bars will be elevated—thus providing a convenient means of adjusting the 35 height of the bars or taking up any wear which may result to their upper faces.

The upper side of the agitator bars is 40 preferably flattened as shown and is provided with a series of inclines 28 which are in position to engage the under side of a grate bar section and raise it with respect to the preceding and following sections. A single agitating bar may be provided for 45 each section engaging it at its middle, as provided for in the modifications of Figs. 3 and 6; or a pair may be provided for each section, as indicated in Figs. 4 and 5, if a tendency to tilt is observed.

In Figs. 3 and 4 the agitator bars will 50 engage at the points 29 and 30 respectively and at these points there may or may not be provided any special lugs for engaging the agitator bars, the mere engagement of the webs of the sections being sufficient. These points of engagement being below the 55 axis of attachment of the sections to the chains, there will be a tendency for the section not only to rise but also to tilt toward the rear of the furnace as indicated by section Z in Fig. 9.

In the modifications of Figs. 5 and 6 cut 60 out portions 31, or 32 are provided (depend-

ing on whether the section is to have one or two agitator bars). These cut out portions 65 provide engaging surfaces for the agitator bars above the axis of support of the sections and therefore there is no tendency for the sections to tilt around their longitudinal axes.

In Fig. 7 I have illustrated a collar 33, held in position by a set screw 34, which may be placed on the shafts 23 as shown to hold the agitator against lateral displacement. This feature may be employed with 70 advantage with the modifications of Figs. 3 and 4 though I do not limit myself to its use.

As will be evident from Fig 2 the spacing 80 of the inclines 28 need not be uniform throughout the length of the agitator but these inclines may be spaced according to the need for them, more or less being employed according as it is found necessary or advisable. I have also illustrated the 85 agitator as beginning under the rear side of the arch and as extending only part way to the rear of the furnace. I do not wish to limit myself, however, to any particular place for starting or stopping the agitation 90 but may proportion or place the agitators at will as may be found necessary or desirable in treating different kinds of fuel.

The operation of my device will be evident from the above detailed description. 95 The grate bars in their progress toward the rear of the furnace will ride over the inclines 28 and, on account of the freedom given thereto by the elongated openings 19, 20, will be displaced vertically with reference to the conveyer chains and the adjacent 100 grate bars, as indicated at X, Y, in Fig. 1. The action of the device when employed with a grate bar section having its point of contact with the agitator bar below the axis of support of the section is more clearly illustrated in the larger scale 105 drawing of Fig. 8. As will be seen the bar is tilted toward the rear of the furnace and this action aids in clearing the teeth of the 110 respective sections while not tilting the bars far enough to permit fuel falling through.

Having thus described my invention, what I claim and desire to secure by Letters Pat- 115 ent is:

In a mechanical stoker, conveyer chains, a plurality of grate bars mounted directly on said chains, said grate bars having vertically slotted connection with said chains, an 120 agitator bar having inclined planes on its upper surface disposed in the path of the lower portion of said grate bars and inclined planes on its lower surface, transverse shafts supporting said agitator bar 125 and located in coöoperative relation to said

last mentioned planes, and means for imparting movement to said agitator bar in a longitudinal direction, whereby said last mentioned inclines will ride on said shafts and thereby adjust the vertical position of the agitator bar.

In testimony whereof, I have hereunto

affixed my signature in the presence of two witnesses.

FRANCIS MORTON CLARK.
